INVENTOR,
HAROLD SOUTHON,
By *H. S. Southon*

ATTY.

UNITED STATES PATENT OFFICE.

HAROLD SOUTHON, OF PUTNEY, LONDON, ENGLAND.

VISE OR CLAMP.

1,257,755.

Specification of Letters Patent. Patented Feb. 26, 1918.

Application filed January 25, 1917. Serial No. 144,489.

To all whom it may concern:

Be it known that I, HAROLD SOUTHON, a subject of His Majesty the King of England, and resident of Putney, in the county 5 of London, Kingdom of England, have invented certain new and useful Improvements in Vises or Clamps, of which the following is a specification.

This invention relates to improvements in 10 and relating to the construction of vises or clamps and it consists in a vise or clamp with a mounting so constructed as to allow the work held therein to rotate or partly rotate, about an axis passing through, or near 15 to, the upper surface of the work. The object of this construction is to permit the work, to the surface of which a file is being applied, to have a freedom of angular movement in a plane normal to the face of the 20 file so that if the file be not moved truly in the filing plane the work will nevertheless automatically adjust itself to the file surface and will be cut truly thereby.

According to the invention the vise or 25 clamp is constructed with one or more movable jaws carried in a suitable manner by a frame comprising an axle or alined axles, the axis of which lies in a plane passing through or near to the upper edges of the 30 jaws, preferably slightly above the plane of such edges so that the upper surface of the work held in the jaws may be fixed in or near to the plane through which the axis passes. The mounting is preferably so made 35 that the vise or clamp is supported thereon by means of its axle or axles on a suitable half bearing or bearings, but is capable of being lifted off or removed from the bearings or bearing to be used as a clamp.

40 In the example of construction of my invention illustrated in the annexed drawings, the vise comprises a stationary jaw and a movable jaw the direction of movement being parallel to the rocking axis. This 45 method of construction is simple and permits of a ready adjustment of the work so that the center of its face may be placed centrally as regards the axis or more or less rearwardly or forwardly as the worker may 50 desire, the rearward placing of the work causing the file to remove more substance from the forward part of the surface and the forward placing of the work causing the file to remove more substance from the rear-

ward part of the surface when either of 55 these is desired. In these drawings:

Figure 1 is a front elevation of this form of construction;

Fig. 2 is a section on line 2—2 of Figs. 1 60 and 3; and

Fig. 3 is a plan.

The frame *a* of the vise is of crank-like or U shape form, with two projecting rods or pins *b* and *c* and having a common axis. At or near one end of the frame *a* is formed 65 a fixed jaw *d* with suitable facing plate *e*. The portion *f* of the frame forms a bed for guiding the base of the movable jaw *g* having a facing plate *h*. The rod *c* and boss of the frame *a* adjacent to and carrying the 70 rod *c* is hollow and screw-threaded to engage the screw *i*. At the outer end of the screw *i* is a knurled head *j*; and at the end nearer the movable jaw *g* a capstan head *k* is screwed upon the screw *i* and secured by 75 a key *l*. The screw *i* terminates at this end in a cylindrical pin *m* engaging a corresponding socket in the back of the jaw *g*. A groove *n* may be cut in the pin *m* with which 80 engages the end of a grub screw *o* to cause the jaw *g* to be withdrawn when the screw *i* is screwed outward to separate the jaws. If it be desired that the jaw *g* be movable 85 outward by hand the grub screw may be removed or omitted. With this construction 85 the screw *i* may be run up by hand and final pressure given by turning the capstan head by means of a tommy bar placed in one of the holes *p*. The upper edges of the fixed 90 and sliding jaws of the vise are slightly below the axial line of the projecting rods *b*, *c*; the faces of the jaws being at right angles to such axial line.

The mounting consists of a base plate *q* having two posts or uprights *r*, *s* of equal 95 height, at a suitable distance apart, having bearings *t* and *u* at the top, in alinement, and preferably two small uprights *v*, *w* forming stops, limiting the rotation of the vise to an arc of a circle. The projecting 10 rods *b*, *c* of the vise are placed in the bearings mentioned in such a way that the vise may rotate, or partly rotate thereon.

It will be obvious that the construction may be varied in many ways without departing from the spirit of my invention, the example illustrated is only one form of construction which I have selected for illustra- 105

tion as being of simple and cheap character. The jaws may also be made to have their gripping movement at right angles to the rocking axis, but the construction would be 5 more complicated and expensive by reason of the desirability that the jaws should be capable of equal and opposite movements for the purpose of centering the works as regards the axis.

10 What I claim is:—

1. A support, a swinging frame mounted on the support, fixed and movable jaws carried by the swinging frame, an adjusting means for the movable jaw disposed in line 15 with the axis about which the frame is free to swing.
2. A support, a swinging frame mounted on the support, fixed and movable jaws carried by the swinging frame and set below 20 the axis thereof, and adjusting means for the movable jaw disposed in line with the axis about which the frame is free to swing.
3. A support, a swinging frame journaled at opposite ends on the support, fixed and 25 movable jaws on the frame disposed between the journals thereof, and adjusting means for the movable jaw in line with the axis of the swinging frame and passing through a journal thereof and the bearing of the 30 support receiving such journal.

4. A support, a frame of substantially U form having opposed journals at opposite ends mounted in said support, said frame having a fixed jaw at one end, a movable jaw on the frame between the journals thereof, and adjusting means for the movable jaw passing through the journal thereof remote from the fixed jaw and through the bearing of the support in which the said journal is mounted.

5. A U-shaped frame, having a fixed jaw at one end and a journal at the opposite end by which to pivotally mount the frame, a movable jaw mounted on the frame between the fixed jaw and journal, and adjusting 45 means for the movable jaw passing through the said journal of the frame.

6. A support having open spaced bearings, a U-shaped frame having journals at opposite ends to swingingly mount the 50 frame in said open bearings, said frame having a fixed jaw at one end, a movable jaw on the frame, and adjusting means for the movable jaw extending through the journal of the frame remote from the fixed jaw 55 thereof.

In testimony whereof I have hereunto signed my name.

HAROLD SOUTHON.
